UNITED STATES PATENT OFFICE.

ZANE BLAND TAYLOR AND ORLANDO WILSON MOORE, OF ORBISONIA, PENNSYLVANIA.

FOLDING CRATE.

SPECIFICATION forming part of Letters Patent No. 655,283, dated August 7, 1900.

Application filed February 3, 1900. Serial No. 3,838. (No model.)

To all whom it may concern:

Be it known that we, ZANE BLAND TAYLOR and ORLANDO WILSON MOORE, citizens of the United States, residing at Orbisonia, in the 5 county of Huntingdon and State of Pennsylvania, have invented certain new and useful Improvements in Folding Crates; and we do declare the following to be a full, clear, and exact description of the invention, such as will 10 enable others skilled in the art to which it appertains to make and use the same, reference being had to the accompanying drawings, and to the characters of reference marked thereon, which form a part of this specification.

15 This invention relates to new and useful improvements in shipping-crates of the folding or collapsible variety especially adapted for shipping poultry, but also well adapted for more general uses.

20 One object of the invention is to improve upon the invention shown and described in Letters Patent No. 628,500, granted to Z. B. Taylor and O. W. Moore July 11, 1899, and particularly to improve the means of locking 25 the door of the crate and also the top of the crate to the crate proper, so that when the same is folded or collapsed into "returning" position said door cannot be opened until the top of the door has been unlocked preparing 30 the crate into position for use, so that the door is prevented from coming open and being exposed to accident, and the use of the spring is obviated.

Other objects of the invention will become 35 apparent in the course of the following description, and other advantages resulting from the simple means employed, enabling the crate to be readily collapsed or put into position for use as the exigency of the case may 40 require and securely maintaining the various parts in their proper relative positions, will become apparent in the course of the description.

The invention consists in the novel arrangement of parts which will now be described.

In the drawings, Figure 1 is a top plan view 45 of the crate folded, with both the top and door thereof locked, parts being broken away throughout the figure to more clearly illustrate the invention, and a position of the lock-

ing means being shown in dotted lines. Fig. 2 is a detail sectional view taken about on a line *x x*, but showing the crate in position for use, to clearly show the position of the movable locking-rod when the crate is in said position. Fig. 3 is a detail end view of one of the corners of the crate, illustrating the manner of hinging or securing the folding end sections to the end cleats or bars.

Referring to the drawings, the numeral 1 indicates the bottom of the crate, to the ends of which in carrying out our invention we rigidly secure two cleats or cross-bars 2 and 3, which are rabbeted, as shown by the numeral 65 4, for the reception of the rockable bars 5, which form the end bars of the folding end sections 6, which sections are further composed of the horizontal rods 7, rigidly secured in any suitable manner to the said end bars, 70 but preferably by dowel-pins fitted accurately in dowels in the bars. These end bars 5 are hinged in the rabbeted ends of the cleats 2 by means of metallic angle-pieces securely fastened to the bottom of the crate and perforated for the passage of screws which pass through the lower ends of the end bars.

The numeral 8 designates two folding side sections composed of two horizontal rods 9 and 10 and intermediate vertical rods 10', 80 the said rods 9 being reduced at their ends to form dowel-pins 12, (shown in dotted lines, Fig. 2,) which enter dowels 13 in the end bars when the crate is standing up, and the rods 10 have dowel-pins 14, that enter dowels 15 in 85 the cleats and so fit therein that the side sections will be permitted to rock. In order that the side sections will be flush upon the bottom of the crate when folded, we recess the cleats, as indicated by the numeral 16, which 90 receive the dowels of the rods 9.

The top of the crate is composed of side bars 18 and 19, held firmly together at their corners by metallic angle-pieces 20, and are strengthened by transverse bars 20' and 21, 95 which, together with the end pieces, serve as supports for the rods 22.

Slidably mounted upon the two central rods *a* and *b* is a yoke 23, rigidly secured to a locking-rod 24, which slides in and is supported by a yoke 25, and through a perforation 26 in the cross-bar 20 and is adapted to

pass through perforation 27 in the side pieces 28 and 29 of the gate or door 30 and also through the perforation 31 in the end bar 18. The door of the crate is rockably connected 5 to the rods C of the top of the crate and opens upwardly.

The numeral 32 indicates two dowel-pins secured to the inside of end bar 19 and are to enter dowels 33 in the cleat 3 for the purpose of securing the top of the crate at this end when the same is folded, and the same pins enter dowels 34 in the upper rod 7 when the crate is in position for use.

To prevent any lateral motion of the top of 15 the crate and as additional means to keep the crate from collapsing, pins 35 are provided which, when the crate is standing, fit just inside the top rods 7 of the side sections.

The numeral 36 designates a screw-eye secured to the center of the cleat 2, and 20 37 indicates a similar eye secured to the center of the upper rod 7 of one of the end sections, both of which eyes are adapted to be entered by the locking-rod 24, the eye 37 when the 25 crate is unfolded and the eye 36 when it is collapsed.

Assuming now that the crate is folded or in the position shown in Fig. 1, to bring the same to standing position it is only necessary to slide the yoke 23 sufficiently to withdraw its end through the perforation in the end bar of the crate-cover and through the eye 37, when the cover can be lifted up sufficiently to disengage the pins 32 from the 35 dowels 33. The end sections are then rocked to vertical position, which operation is followed by a like movement of the side sections, and after the dowel-pins of the top rods of the side sections are seated in the 40 dowels of the end sections the top is then put in place, the pins 32 entering the dowels in the top rods 7 of the end sections, and when the top is in position upon the crate the locking-rod is shifted sufficiently to pass 45 through the eye 37 and the perforation in the end bar 18, thus locking the crate-cover firmly in place and also maintaining the door locked. The yoke 23 is prevented from moving nearer to the eye 36 than the position 50 shown in Fig. 1 by coming in contact with the rod 7, thus preventing the door from being opened while the crate is locked in collapsed position.

To unlock the door, the locking-bar is shifted 55 sufficiently to withdraw its end from the perforation in the side bar of the door.

Having thus described our invention, what we claim as new, and desire to secure by Letters Patent, is—

1. In a crate, the combination with a cover 60 provided with overhanging side bars and dowel-pins, of folding side and end sections, the top rails of the side sections being provided with dowel-pins adapted to enter dowels in the end sections when the crate is in 65 position for use, a screw-eye or its equivalent carried by the end section, and a sliding rod adapted to enter said eye when the crate is standing, to lock the cover in place, a suitable bottom board and means for locking the 70 cover on the crate when collapsed, substantially as set forth.

2. In a crate, the combination of a bottom section, side and end sections foldably secured thereto and means for securing them 75 together in vertical position, a screw-eye or its equivalent carried by the top rail of one end section and the top rail of the other section being recessed, of a cover provided with overhanging side and end bars and carrying 80 projections on the inside of one end bar and having a perforation in the other, a hinged door in said cover, a slidable locking-rod carried by said cover and adapted to pass through the eye on the top of the rail of the folding 85 end section and into the perforation in the end bar of the cover and engage the door, and the projection on the end bar entering the recesses in the folding end section at the same time, thereby locking the cover to the 90 crate proper and also the door in said cover when the crate is in standing position, as set forth.

3. In a crate, the combination with a suitable bottom section having cleats secured to 95 the ends thereof, one of said cleats provided with recesses and the other with a screw-eye or its equivalent, of folding side and end sections adapted to be secured together in vertical position, of a cover provided with overhanging side and end bars and carrying projections on the inside of one end bar and having a perforation in the other, a locking-rod 100 slidably mounted on the cover and adapted to enter the eye carried by the cleat and the 105 perforation in the end bar of the cover, and a door rockably secured to said cover and adapted to be engaged by the locking-rod and the pins or projections adapted to enter the recesses in the cleat, all substantially as 110 set forth.

In testimony whereof we affix our signatures in presence of two witnesses.

ZANE BLAND TAYLOR.

ORLANDO WILSON MOORE.
